CHAIN CANDLE

Siegfried Steinhart, 14 Obere Ganshalde,
8908 Krumbach, Germany

Filed Jan. 10, 1974, Ser. No. 432,327

Claims priority, application Germany July 19, 1973

Term of patent 14 years

Int. Cl. D26—04

U.S. Cl. D73—1 B

The figure is a side perspective view of a chain candle, the appearance of each segment being the same from all sides and the lower six segments being shown as though resting on a surface.

I claim:

The ornamental design for a chain candle, as shown and described.
